(57) **CLAIM**

The ornamental design for a display screen or portion thereof with graphical user interface of raman microscope, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface of raman microscope showing a first embodiment of our new design;

FIG. 2 is a front view of a display screen or portion thereof with graphical user interface of raman microscope showing a second embodiment of our new design; and,

FIG. 3 is a partial enlarged view of the claimed design portion in FIG. 2.

The outermost dash-dot broken lines illustrate a display screen or portion thereof and form no part of the claimed design. The gray overlay in FIG. 2 illustrates the remaining graphical user interface that forms no part of the claimed design. The dot-dash broken lines indicate the location and boundary of the enlarged partial view. None of the broken lines form part of the claimed design.
